UNITED STATES PATENT OFFICE.

WILLIAM F. SCHWEIGER, OF ROCHESTER, NEW YORK, ASSIGNOR TO MULTIPOST COMPANY, INCORPORATED, OF ROCHESTER, NEW YORK, A CORPORATION OF NEW YORK.

STAMP-AFFIXING MACHINE.

Application filed September 5, 1924. Serial No. 736,074.

To all whom it may concern:

Be it known that I, WILLIAM F. SCHWEIGER, a citizen of the United States of America, residing at Rochester, in the county of Monroe and State of New York, have invented certain new and useful Improvements in Stamp-Affixing Machines, of which the following is a specification.

This invention relates to a stamp affixing machine, with more particular reference to the type in which certain manually controlled devices cooperate to feed a stamp strip, moisten an envelope, sever a stamp, and affix it to the moistened portion of the envelope.

The purpose of the invention is to provide cancelling mechanism which will print or mark on an envelope adjacent to or to one side of the stamp or stamp receiving zone, such operation being desirable for instance in connection with pre-cancelled stamps for the purpose of imposing a cancellation or dating mark on the envelope at the time the stamp is affixed thereto.

Another object of the invention is to provide cancelling mechanism for the purpose mentioned, and arranged so as to be automatically operated by or in conjunction with the stamp affixing mechanism, and preferably at the same operation that feeds and affixes the stamp.

With these ends in view, the invention embodies the principle that will be more clearly understood from the following description, when read in conjunction with the accompanying drawing, the novel features being pointed out in the claims following the description.

In the drawing:

Figure 1 is a sectional view of a stamp affixing machine incorporating the invention in one practical form, and with the parts in normal or uppermost position;

Figure 2 is a similar view, partially broken away, with the parts in their lowermost operating position;

Figure 3 is a transverse vertical sectional view on line 3—3 of Figure 1, and

Figure 4 is a detail view of a portion of an envelope, showing a stamp affixed and cancelled.

The underlying idea forming the basis of this invention may be carried out in a number of ways, and this disclosure is intended merely to illustrate one practical arrangement, as an example of the scheme of operation and function of the improvement.

Referring to the structure disclosed, 1 designates a housing carrying a base 2 and container 3 for the stamp strip or roll 4, which is moved to position over the envelope and severed by the usual feeding and cutting devices employed in this type of machine. Said feeding and cutting devices are mounted on a vertically movable plunger 5 carrying the usual handle 6 by which the machine is manually operated.

The plunger 5 carries at its lower end a foot 7 which engages and affixes the stamp to the envelope after it is severed from the strip, the envelope being first moistened by water that is ejected from a water compartment 8, through suitable openings and by means of a water ejecting device 9 which is normally in the position shown in Figure 3, and operated through a rod 10 and pivoted cam 11. The latter is engaged by the arbor 12 during the downward movement of the plunger 5 so as to cause the water ejecting device 9 to move inwardly, while upon the upstroke of the plunger, the arbor 12 swings the cam 11 on its axis upwardly and rides past it. The moistening mechanism just described forms no part of the present invention, but is substantially in accordance with prior stamp affixing apparatus.

Where pre-cancelled stamps are used, it is desirable to impose a cancelling and dating mark on the envelope, or on the envelope and stamp, at the time the latter is affixed, such cancellation mark preferably extending over the stamp and over the area of the envelope alongside of or adjacent to the stamp, as illustrated in Figure 4. The cancellation mark on the stamp itself may be taken care of by suitable printing means

carried by the foot 7 and serving to mark upon the stamp at the same time that the latter is pressed upon the envelope. In order to impose the necessary cancellation mark 5 on the zone of the envelope to one side of or adjacent to the stamp zone, an independent cancelling device is employed, which is preferably operated automatically at the same time that the stamp is affixed.

This may be accomplished in different ways, and one method consists in mounting a cancelling device or printing pad 15 on an arm 16, the latter being carried by the foot 7. The printing pad 15 is preferably 15 resiliently held on the arm 16 through a spring 17, so that it may yield when engaging the envelope, preferably moving slightly in advance of the foot 7, as shown in Figure 1. The plunger 5 and parts just described 20 are held in normal or upward position by the spring 18, while 19 is an inking roller mounted on an arm 20 which is pivoted at 21 and spring-operated to hold it in the position illustrated in Figure 1. As the parts 25 move downwardly, the inking roller 19 is actuated laterally to the position shown in Figure 2, and during such operation wipes over the surfaces of the printing devices on foot 7 and printing pad 15, the roller being held 30 in disengaged position by the upwardly extending ledge 22. Ink may be supplied to the roller 19 when necessary through an opening 23 provided with a movable cover 24.

35 In operating the machine, it is placed over an envelope with the foot 7 above the stamp zone illustrated in Figure 4. The plunger 5 is pressed downwardly, causing water to be ejected on to the stamp zone of the envelope, while at the same time the stamp strip is fed sufficiently to eject a stamp, the latter is severed from the strip when in its 40 position over the envelope and immediately following, the foot 7 engages the stamp and 45 by the pressure of the plunger, forces it into close engagement with the envelope. At the same time, the printing devices on the foot 7 impose the dark lines or other suitable cancellation mark on the stamp.

50 Immediately following the pressing of the stamp upon the envelope, or simultaneously therewith, the independent cancelling device 15 comes into engagement with the envelope at a point alongside the stamp, and imposes a dating or other suitable cancellation mark 55 upon the envelope. The cancellation mark upon the envelope alongside the stamp may be either in conjunction with, or a portion of, the mark upon the stamp, or the cancellation mark upon the stamp may be omitted, if desired.

While the invention has been described with reference to a particular mechanism, it is not limited to the arrangement or details 60 herein described, but is susceptible of modi-

fications or departures such as come within the intent and purpose of the improvement or the scope of the following claims.

I claim:

1. In a hand-operated stamp affixing machine, the combination with means for feeding a stamp strip to a predetermined point on an envelope, of a manually operated plunger operatively associated with the strip feeding means, and a cancelling device arranged and operable so as to print on the envelope immediately adjacent to the predetermined stamp receiving zone. 70

75 2. In a hand-operated stamp affixing machine, the combination with means for feeding a stamp strip, of a manually operated plunger operatively associated with the strip feeding means, a stamp engaging foot carried by said plunger, and a cancelling device movable independently of the foot and operated automatically during movement of the latter. 80

85 3. In a hand-operated stamp affixing machine, the combination with means for feeding a stamp strip, of a manually operated plunger operatively associated with the strip feeding means, a stamp engaging foot carried by said plunger, cancelling means carried by the foot for printing on the stamp, and independent cancelling means movable independently of the foot and operable for printing on the envelope adjacent to the stamp. 90

95 4. In a hand-operated stamp affixing machine, the combination with means for feeding a stamp strip to a predetermined point on an envelope, of a manually operated plunger operatively associated with the strip feeding means, a cancelling device arranged 100 to print on an envelope at one side of and immediately adjacent to the stamp receiving zone, and means acting automatically as the stamp is affixed to operate said cancelling device. 105

110 5. In a hand-operated stamp affixing machine, the combination with means for feeding a stamp strip to a predetermined point on an envelope, of a manually operated plunger operatively associated with the strip feeding means, a stamp engaging foot carried by said plunger, and a cancelling device 115 arranged to one side of the foot and controlled by the plunger, the cancelling device being movable independently of the plunger and acting to print on the envelope immediately adjacent to the predetermined stamp receiving zone. 120

125 6. In a hand-operated stamp affixing machine, the combination with means for feeding a stamp strip to a predetermined point on an envelope, of a manually operated plunger operatively associated with the strip feeding means, and a cancelling device arranged to print on an envelope at one side of the stamp receiving zone, the cancelling 130

device being controlled by said plunger, and movable independently thereof.

7. In a hand-operated stamp affixing machine, the combination with means for feeding a stamp strip to a predetermined point on an envelope, of a manually operated plunger operatively associated with the strip feeding means, a stamp engaging foot car-

ried by said plunger, and a cancelling device carried by the plunger and located to one side of said foot, the cancelling device being movable independently of the plunger. ¹⁰

In witness whereof, I have hereunto signed my name.

WILLIAM F. SCHWEIGER.
